COIN CONTROLLED MECHANISM

Francis C. Du Grenier, Haverhill, Mass., assignor
of one-half to Blanche E. Bouchard, Haverhill,
Mass.

Application October 29, 1935, Serial No. 47,255

14 Claims. (Cl. 194—71)

This invention relates to that class of vending machines in which the dispensing mechanism is normally released upon the insertion of a plurality of coins and which are primarily designed for vending packages of cigarettes, which at the present time are sold at prices ranging from 10 to 20 cents per package.

In many States a tax of several cents is levied on each package of cigarettes sold, which is collected at the time of the sale, and if a tax of 2 cents, for example, is levied on a package of cigarettes selling for 15 cents, it is considered that the most practical way of handling the sale in a vending machine is to require the purchaser to place 20 cents in the machine and have the machine deliver 3 cents change with the package, this being done by the simple method of arranging a change ejector in connection with the package ejector, so that, when the latter is operated, the necessary change will be delivered.

As no sales tax is required in many States, there is a demand for a machine of this type which may be operated when 15 cents is placed in the machine, and it is therefore desirable that a machine be produced which may be employed, by making adjustments, to vend packages at either 15 or 20 cents, or at an intermediate price.

The primary object of my invention is to produce a machine of the above described type which, by making a simple adjustment of a part of the coin controlled mechanism, may be converted from a machine which will release the locking mechanism when 3 nickels and a dime have been inserted, to a machine which will release it when 4 nickels, or 2 nickels and a dime have been inserted.

A further object is to provide a single device for releasing the locking means of the dispensing mechanism which will be operative on the insertion of the several coins which are required for delivery of a package, as for example a nickel and a dime, or three nickels, or in case the amount to be inserted is 20 cents, two nickels and a dime, or four nickels.

Another object is to provide a simple attachment whereby one or more of the dispensing devices may be released on the insertion of a single coin, as when it is desired to vend some of the packages at 10 cents.

Further objects are to provide a simplified form of coin controlled mechanism in which all coins in excess of the required number will be immediately returned to the purchaser, or in which the purchaser may secure the return of all

coins which have been inserted prior to the operation of the dispensing mechanism.

I accomplish these objects, and other objects to be referred to, by means of the apparatus hereinafter described and illustrated in the accompanying drawings in which:

Fig. 1 is a view in elevation of the coin controlled mechanism, embodying my invention, which is mounted on the right hand end of the machine casing.

Fig. 2 is a sectional view, at line 2—2 of Fig. 1.

Fig. 3 is a vertical sectional view, at line 3—3 of Fig. 10.

Fig. 4 is a view similar to Fig. 1, with some of the parts removed, showing the adjustment for 4 nickels, or 2 nickels and a dime.

Fig. 5 is a view of the parts as adjusted in Fig. 4, in a different position, and as viewed from the opposite side.

Fig. 6 is a detail view of the coin supporting 20 member.

Fig. 7 is a detail view, similar to Fig. 5, showing the adjustment for operation by 3 nickels, or 1 nickel and a dime.

Fig. 8 is a detail view showing a dime in position 25 on its support.

Fig. 9 is a view illustrating the operation by a dime only.

Fig. 10 is a sectional view at line 10—10 of Fig. 9.

Fig. 11 is a sectional view at line 11—11 of Fig. 10.

Fig. 12 is a detail perspective view illustrating the action of the releasing dog and associated parts.

In general, the machine illustrated is of the common type in which a series of vertical package containing columns 13 (Figs. 3 and 10) are provided, at the bottom of each of which a reciprocating ejector 14 is provided which is operated by a handle 15. In normal operation a handle is pulled out, so that the bottom package in the corresponding column falls in the rear of the ejector to which the handle is attached and the package is ejected into the passage 16, on the return movement, so that it slides down and is delivered on the tray 17 at the front of the machine. Each ejector is provided with a hook 18, which is arranged to engage a crank arm 20, said arm extending the entire width of the machine and being pivotally mounted in the casing at each end, so that, when any ejector is pulled forward, the arm is swung forward thereby, the movement being permitted or prevented according to whether the arm is locked 55

or unlocked at its bearings. A segment 22 is secured on the right hand end of crank arm 20 and is provided with teeth arranged to be engaged by a pawl 24, so that, when a dispensing operation is started, the ejector must be pulled out to its limit before it can be returned by spring 21, which is attached to segment 22. A locking lever 26 is mounted on a pivot 27 which passes through a longitudinal slot 28 therein, to permit an initial longitudinal movement of the lever thereon, and said lever has a notch 29 therein, which receives the top end of a rigid arm 30 on the segment 22, said lever being normally held down on said arm by a spring 32. With this arrangement, if any one of the handles 15 is pulled out, a slight outward movement of lever 26 will first be permitted sufficient to operate levers 34 and 36, by a cam 37 on lever 26, which engages lever 34 and acts, through lever 36, to dislodge and return any coins or slugs which may have been intercepted by the coin testing means (not shown), and then the lever 26 will lock the segment 22 against further swinging movement, so that further outward movement of the ejector to which the handle is attached will be arrested. If, however, lever 26 should be lifted out of engagement with the arm 30 just before the locking action takes place, the movement will be permitted.

30 The means whereby the dispensing mechanism will be unlocked on the insertion of suitable coins will now be described.

According to my invention two main coin-receiving passages 38 and 40 are provided, which are arranged side by side, (see Fig. 2), and into which the coins are discharged from the coin testing means, in the present instance the passage 38 being adapted to receive a nickel and the passage 40 a dime, and a branch passage 39 leads from one side of the passage 38. It will be understood that the entrances to said main passages are at the front of the machine, as is customary.

A coin supporting member 42, shown in detail in Fig. 6, is mounted on pivots 43 at its lower end, so that it may be swung outward from the casing against the action of a spring 44. Said member is provided with three coin-supporting shelves 45, 46, 47, which project at right angles therefrom, the shelves 45 and 46 being formed integrally therewith and the shelf 47 consisting of a right angularly shaped strip, the shank portion of which is attached to member 42 by screws 48, which pass thru a longitudinal slot 49 therein, so that the position of the shelf 47 may be vertically adjusted by merely loosening screws 48 and moving the part up or down. The shelf 45 extends into the dime slot 40, so that when a dime is placed in the passage it will come to rest thereon, as shown in Fig. 8. The shelf 47 extends into the lower end portion of the nickel slot 38, and, as shown in Figs. 5 and 7, may be adjusted to two positions. In the position shown in Fig. 5 it is adjusted to support two nickels on edge, so that one rests on the other, and in the position of Fig. 7 a single nickel only will come to rest thereon. The adjustment is such that the topmost coin of the two coins and the single coin will be held in substantially the same positions, in which position, if an additional nickel is placed in the slot, it will strike the topmost nickel, or the single nickel, as the case may be, and will be deflected into the branch passage 39 and will come to rest on the shelf 46, which is located at the bottom thereof. The shelf 46 is so arranged that two nickels may be placed in the

branch passage, so that they will rest edge to edge one on the other, as shown in both Figs. 5 and 7, the top nickel being thus supported side by side with the position in which the dime is held on shelf 45, with its top edge at approximately the same level as the top edge of the dime, as indicated by the dotted line positions of Fig. 12. It is not to be understood that the dime and the top nickel in the branch passage will both be supported in this position at the same time. To prevent such an occurrence a retaining device for the dime is provided which consists of an arm 50, which is suspended from a pivot 51 and has two fingers 52 and 53. (See Fig. 10.) When in normal position the finger 52 extends into the dime slot in such a position that it holds the dime on the shelf 45, as shown in Fig. 8, and, if the finger 52 is withdrawn from this position, the dime will immediately roll from the shelf and pass into the coin return passage 58 at the rear thereof and pass down onto the package shelf 17. The finger 53 extends into the branch nickel slot 39 and has an inclined end face normally so arranged that when a nickel passes into the branch slot it will engage said inclined face and swing the arm 50 outward to a sufficient extent to withdraw the finger 52 from its dime engaging position. The discharge of the dime in this manner is facilitated by so forming the supporting shelf 45 in inverted V-shape, so that the dime normally rests on a sharp ledge at one side of its middle, as shown in Fig. 8, and when the finger 52 is withdrawn the dime will immediately fall into the return passage. Consequently, after a nickel has passed into the branch slot, if a dime is inserted it will be immediately returned, or if a dime is first inserted and then a nickel passes into the branch slot, the dime will be returned. In either instance the coin last inserted would be in excess of the amount required to unlock the machine and permit the dispensing operation.

On account of the fact that dimes are thin and by use become worn thinner, difficulty has been encountered in having the dime first inserted act to deflect a second dime, inserted by mistake, into the return passage. For this reason an auxiliary deflector is provided, which consists of a finger 54, mounted on a pivot 55, said finger being normally held by its gravity in a nearly balanced position, as shown in Figs. 1 and 4 and in dotted lines in Fig. 9. The arrangement is such that when a dime comes to rest on the shelf 45, it bears against a projection 56 on the finger, and, by its weight, causes the finger to swing slightly, so that its top end then extends into the dime passage to the position shown in Fig. 8, so that after one dime has been inserted, and before the dispensing mechanism is operated, if a second dime is inserted by mistake, it will strike the top end of finger 54, as indicated in Fig. 8, and be deflected into the return passage 58, which opens into the delivery passage 16.

As previously noted, the lever 26 normally locks the dispensing mechanism against operative movement, and, when lifted sufficiently to permit arm 30 on segment 22 to swing forward, the dispensing operation will be permitted.

According to my present invention, a releasing dog 60, shown in detail in Fig. 12, is mounted on a pivot 61 in the lever 26, said pivot being located adjacent the middle of the dog, which is adapted to tilt freely on its pivot. Fingers 62 and 63 extend at right angles from each end of the dog, 75

the finger 62 being arranged to be carried into engagement with the top edge of the nickel or top nickel on support 47 in the main nickel slot, as shown in Figs. 5 and 7, and the finger 63 being arranged to be carried into engagement either with the top edge of a dime on the support 45, or with the top edge of the top nickel on the support 46 in the branch passage, as shown in Figs. 5, 7, and 12, said finger 63 extending across both positions, the positions in which the dime and the top nickel in the branch passage are held being at approximately the same level at their top edges, it being understood that at no time are both the dime and the nickels in the branch passage held on their supports, but that either one or the other must be so held to permit release of the dispensing mechanism, as will now be explained.

As thus arranged, on the initial movement of the dispensing mechanism, the lever 26 will be carried forward, causing the fingers 62, 63 of the dog 60 to engage simultaneously the nickel in the main nickel slot, and either a dime in the dime slot or the top nickel in the branch slot, (see Fig. 12) so that, as the lever 26 is drawn forward, the fingers will ride up on the coins, causing the dog to be lifted bodily, thereby lifting the lever 26, so that it will be disengaged from the arm 30, thereby permitting the dispensing operation to be performed. It will be noted that, to make this action possible, both fingers 62 and 63 must be engaged with coins, for if only one of them is engaged, the dog will be merely tilted on its pivot, and no lifting action on the lever 26 will take place.

As shown in Fig. 12, the dog 60 is also provided with a third finger 64, which is disposed above finger 62 and functions with the finger 63 under the following conditions, when it is desired to dispense a package from one or more of the columns, on the insertion of a dime only.

If a 10 cent package is to be dispensed from the first and second right hand columns, a bracket 65 is mounted on the casing in front of the ejectors of these columns and a bar 66 is slidably mounted thereon, said bar having inclined projections 67, 68 which extend slightly into the paths of the ejectors, so that, when either ejector is pulled forward, the bar will be moved to the right for a short distance. Said bar 66 extends thru the end casing and has a finger 69 extending at right angles thereto, (see Figs. 1 and 11). A spring 70 engages the outer side of finger 69 and normally holds the bar 66 in position to be engaged by the ejectors and also holds finger 69 in an inoperative position. When, however, if either of the two ejectors are pulled out, it will immediately engage the bar 66 and push it to the right, in which position finger 69 will be moved into a position directly in front of the finger 64, so that, on further dispensing movement the in-turned end of finger 64 will ride up on finger 69 and thus act to support the outer end of the dog 60 in the same manner that it is supported by the engagement of finger 62 with the nickel in the main nickel slot, as shown in Fig. 12, so that, if a dime has previously been inserted, the lever 26 will be lifted to its inoperative position, permitting the dispensing operation to be performed.

A cam face 72 on the segment 22 moves into engagement with the inner side of the coin supporting member 42 when the segment has been advanced beyond the position in which it may be locked by lever 26 and swings the member outward, withdrawing the coin supports from be-

neath the coins which are supported thereon, so that the coins all fall into the money box and are retained.

To insure retention of the dime after the dispensing operation is started, a spring arm 74 is mounted on the casing and has an inturned end portion 74', which is normally held in an inoperative position by a lug 75, on lever 26, when the latter is in its rearmost position. When the lever 26 is moved forward slightly, the spring arm 74 is permitted to swing inward to a position in which it will prevent a coin on support 45 from passing into the return passage. This arrangement is provided to prevent the dime from being returned after it has functioned to unlock the segment 22 and before it has been discharged into the money box, in case it should be attempted to secure the return of the dime by striking the machine a sharp blow.

Means are also provided for securing the return of all coins which have been inserted at any time before the dispensing operation is performed. This comprises a push rod 76 having a cam face 77, which is arranged to engage an arm 78 on the coin supporting member 42, so that, when the rod is pushed inward, the member will be swung outward, withdrawing the coin supports from beneath the coins. To prevent the coins from falling into the money box, a deflector 80 is provided, which is mounted on a pivot 81 and has a pin 82 projecting outward at its lower end arranged in the path of movement of a projection 83 on the inner end of push rod 76, so that, when rod 76 is pushed inward, the deflector 80 will be swung from the dotted line position of Fig. 3, in which position all coins falling from the coin supports upon their withdrawal will be discharged into the money box, to the full line position of Fig. 3, in which position all coins falling from the coin supports will be deflected into the return passage, or package chute 16. The arrangement is such that when rod 76 is pushed inward, the deflector will be swung to coin restoring position before the cam 77 engages the arm 78, and moves out the member 42 sufficiently to dump the coins. It is to be noted that there is no positive connection between the push rod 76 and the deflector 80, so that, when the rod is returned by its spring 84, the deflector will remain in its coin restoring position. The reason for this is, that the operator is liable to push the rod 76 and then permit it to spring back quickly before all the coins have had time to fall onto the deflector and be returned, so that if the deflector was returned to normal almost instantly, some of the coins might fall into the money box instead of being returned, but, as the deflector remains in coin returning position after the rod springs back to its original position, it is not possible for this to occur.

It is however essential that the deflector 80 be returned to coin receiving position at the beginning of the next dispensing operation and also that the coin returning means be locked against operation as soon as a dispensing operation is started. To perform the latter function, a pin 85 is mounted on the segment 22, which passes into a slot 86 in the push rod 76, at the beginning of the dispensing movement. Also a lever 87 of 70 spring material is pivoted on a stud 88 in the push rod 76, one arm of which is arranged to be engaged by pin 85 and the other arm of which is arranged to press on the pin 82, which projects from the deflector 80, so that, as the pin 85 is 75

5 moved up in the slot 86 it will press upward on one arm of lever 87 causing the other arm thereof to press down on pin 82, and immediately return the deflector 80 to coin receiving position before there is any possibility that the coins on the supports will be dumped therefrom.

10 In the present apparatus change making devices are employed when the packages are sold at prices between 15 and 20 cents, which are operated by the respective ejectors, but as they constitute no part of the present invention they are neither shown or described.

I claim:

1. In a coin controlled dispensing mechanism, 15 a pair of coin supports each arranged to hold a coin on edge in a predetermined position, a locking device normally disposed to lock said mechanism against operative movement, a tiltable releasing device mounted on said locking device 20 having oppositely disposed faces arranged for simultaneous engagement with the edges of coins on said supports, means, arranged to be actuated by an initial movement of said dispensing mechanism, to move said locking device to engage said faces with coins on said supports and on further movement of said mechanism, to move said locking device in a direction to permit the coins to deflect said releasing device laterally and thereby move said locking device to an inoperative position and permit continued operative movement 25 of said mechanism and means operative to discharge the coins from said supports after said mechanism has been moved to a point where it may no longer be locked.
2. In a coin controlled dispensing mechanism, 30 a first main passage and a second main passage for coins of different denominations, said first main passage having a branch passage leading therefrom, a coin support at the bottom of each 35 main passage and the branch passage, the support of the first main passage being arranged to support a coin in position to deflect a coin subsequently inserted into said branch passage and the support in the branch passage being arranged to 40 support a plurality of coins with the topmost coin adjacent the position in which a coin is held on the support of the second main passage, a locking device normally acting to lock said dispensing mechanism against operative movement, 45 a releasing device operative to hold said locking device in an inoperative position, on operative movement of said dispensing mechanism, when simultaneously engaged with a coin on said first main passage support and with a coin either on 50 said second main passage support or on said branch passage support, and means operative to discharge the coins from said supports when said mechanism has been moved beyond a point where it may be locked.
3. In a coin controlled dispensing mechanism, 55 a first and a second main passage for coins of different denominations, said first main passage having a branch passage leading therefrom, a coin support at the bottom of each main passage, and at the bottom of said branch passage, the support at the bottom of the first passage being arranged to support a coin in position to deflect a coin subsequently inserted into said branch passage, 60 and the support in said branch passage being arranged to support a plurality of coins with the topmost coin adjacent the position in which a coin on the support of the second main passage is held, a locking device normally disposed to lock said dispensing mechanism against operative movement, a releasing device operative to 65

move said locking device to an inoperative position on operative movement of said dispensing mechanism, when simultaneously engaging with a coin on the support of the first main passage and with either a coin on the support of the second main passage or the topmost coin on the support of said branch passage, and means operative to discharge the coins from said supports when said mechanism has been moved beyond a point where it may be locked.

4. In a coin controlled dispensing mechanism, 10 having a first and a second main passage for coins of different denominations, said first main passage having a branch passage leading therefrom, a coin support at the bottom of both main 15 passages and the branch passage, each arranged to support a coin on edge, the support in said first main passage being arranged to support a coin in position to deflect coins subsequently inserted into said branch passage and the support in said branch passage being arranged to support a plurality of coins one above another edge to edge, so that the topmost coin will be supported side by side with the position in which a coin is supported on the support of said second main passage, a locking device normally acting to lock said dispensing mechanism against operative movement, releasing means on said locking device arranged for simultaneous engagement with the top edge portion of a coin on said first 20 main passage support and with the top edge portion of either a coin on said second main passage support, or the topmost coin on said branch passage support, said releasing means being operative to hold said locking device in an inoperative position only when thus simultaneously engaged, on operative movement of said dispensing mechanism, and means operative to discharge the coins from said supports after said locking device has been moved to inoperative position.

5. In a coin controlled dispensing mechanism, 25 having a first and a second main passage for coins of different denominations, said first main passage having a branch passage leading therefrom, a coin support at the bottom of both main 30 passages and the branch passage each arranged to support a coin on edge, the support in said first passage being arranged for adjustment to support a single coin or the topmost of a plurality of coins in a position to deflect a coin subsequently inserted into said branch passage, a locking device normally acting to lock said dispensing mechanism against operative movement, 35 releasing means operative to hold said locking device in an inoperative position on operative movement of said dispensing mechanism, when simultaneously engaged with the coin or the topmost coin on said first main passage support and with either a coin on said second main passage support or a coin on said branch passage support, 40 and means operative to discharge the coins from said supports after said locking device has been moved to inoperative position.

6. In a coin controlled dispensing mechanism, 45 having a first and a second main passage for coins of different denominations, said first main passage having a branch passage leading therefrom, a coin support at the bottom of both main 50 passages and the branch passage, each arranged to support a coin on edge, the support in said first main passage being arranged for vertical adjustment to support a single coin or the topmost of a plurality of coins in a position to deflect a coin subsequently inserted into said branch passage, and the support in said branch 55 pas-

5 sage being arranged to support a plurality of coins edge to edge, so that the topmost coin will be supported adjacent the position in which a coin is supported on the support of said second main passage, a locking device normally acting to lock said dispensing mechanism against operative movement, releasing means operative to hold said locking device in an inoperative position on operative movement of said dispensing mechanism when simultaneously engaged with a coin, or the topmost coin on said first main passage support, and with either a coin on said second main passage support or a coin on said branch passage support, and means operative to 10 discharge the coins from said supports after said locking device has been moved to inoperative position.

10 7. In a coin controlled dispensing mechanism having a plurality of operating devices and a 20 pair of coin passages for coins of different denominations, supports at the bottom of said passages for holding coins thereon in predetermined positions, a locking device normally acting to lock said dispensing mechanism against operation by any one of said operating devices, releasing means operative to hold said locking device in an inoperative position on operative movement of said dispensing mechanism when simultaneously engaged with a coin on both of said supports, means arranged for actuation on operative movement of one of said operating devices into a position to be engaged by said releasing means simultaneously with the engagement thereof with a coin on one of said supports, to function 30 therewith to hold said locking device in its operative position, and means operative to discharge the coins from said supports after said dispensing mechanism has been moved beyond a point where it may be locked.

40 8. In a coin controlled dispensing mechanism having a plurality of operating devices and a pair of coin passages for coins of different denominations, supports at the bottom of said passages for holding coins thereon in predetermined 45 positions, a locking device normally disposed to lock said dispensing mechanism against operation by any one of said operating devices, releasing means operative to move said locking device to an inoperative position on operative movement 50 of said dispensing mechanism when simultaneously engaged with a coin on both of said supports, means arranged for actuation on operative movement of one of said operating devices into a position to be engaged by said releasing means 55 simultaneously with the engagement thereof with a coin on one of said supports, to function therewith to move said locking device to its inoperative position, and means operative to discharge the coins from said supports after said locking device 60 has been moved to its inoperative position.

65 9. In a coin controlled dispensing mechanism having coin receiving and coin restoring passages, a coin support disposed at the entrances to said passages, means, arranged to be actuated by an operative movement of said dispensing mechanism, to move said support to deliver a coin thereon to said receiving passage, a deflector disposed between the entrances to said passages and movable between positions to direct a coin 70 discharged from said support into either of said passages, a coin restoring device movable from its normal position successively to move said deflector to its coin restoring position and then to move said coin support to discharge a coin therefrom and means to return the deflector to coin

receiving position, after said coin restoring device has been returned to normal position.

10 10. In a coin controlled dispensing mechanism having coin receiving and coin restoring passages, a coin support disposed at the entrances 5 to said passages, means, arranged to be actuated by an operative movement of said dispensing mechanism, to move said support to deliver a coin thereon to said receiving passage, a deflector disposed between the entrances to said passages 10 and movable between positions to direct a coin discharged from said support into either of said passages, a coin restoring device movable from its normal position successively to move said deflector to its coin restoring position and then to 15 move said coin support to discharge a coin therefrom, means to retain said deflector in coin restoring position when said restoring device is returned to normal position, and means operated by an initial movement of said dispensing mechanism to return said deflector to coin receiving position.

11. In a coin controlled dispensing mechanism having coin receiving and coin restoring passages, a coin support disposed at the entrances 25 to said passages, means, arranged to be actuated by an operative movement of said dispensing mechanism, to move said support to deliver a coin thereon to said receiving passage, a deflector disposed between the entrances to said passages 30 and movable between positions to direct a coin discharged from said support into either of said passages, a coin restoring device movable from its normal position successively to move said deflector to its coin restoring position and then to 35 move said coin support to discharge a coin therefrom, means to retain said deflector in coin restoring position when said restoring device is returned to normal position, and means operated by an initial movement of said dispensing 40 mechanism to lock said restoring device against operative movement and to return said deflector to coin receiving position.

12. In a coin controlled dispensing machine having a coin returning passage, a first and a 45 second main coin receiving passage for coins of different denominations and a branch passage leading from said first main passage, coin supports in each of said main and branch passages, and a retaining device normally operative to prevent a coin deposited on the support of said second main passage from passing into said return passage and arranged to be displaced by a coin deposited on the support of said branch passage and moved to a position to permit a coin on the 55 second main passage support to pass into the return passage.

13. In a coin controlled dispensing mechanism, a locking device normally operative to lock said mechanism against operative movement, a pair 60 of coin supports arranged to hold two coins in adjacent positions, a tiltable releasing device pivotally mounted on said locking device and having faces oppositely disposed with relation to its pivot and arranged for simultaneous engagement respectively with coins held on said supports, means, arranged to be actuated by an initial movement of said dispensing mechanism, to move said locking device to engage the faces of said releasing device with the coins on said supports and hold 65 said locking device in an inoperative position, and means operative to discharge the coins from said supports after said releasing device has operated to permit operative movement of said dispensing mechanism.

14. In a coin controlled dispensing mechanism, a pair of coin supports arranged to hold two coins in adjacent positions, a locking lever normally operative to lock said mechanism against complete operative movement, a tilttable releasing device pivotally mounted on said lever and having faces oppositely disposed with relation to its pivot and arranged for simultaneous engagement, respectively, with coins held on said supports, means, arranged to be actuated upon an initial operative movement of said dispensing

mechanism, to move said lever to engage the faces of said releasing device simultaneously with coins on said supports, whereby said device will be operative to hold said lever in an inoperative position until said mechanism has been moved beyond a point where it may be locked thereby, and means operative to discharge to coins from said supports after said mechanism has been moved beyond said point. 5

FRANCIS C. DU GRENIER. 10
